UNITED STATES PATENT OFFICE.

BENJAMIN F. CRISENBERRY, OF INDIANAPOLIS, INDIANA.

DESIGN FOR A FOOD-MASHER.

56,119.

Specification for Design. Patented Aug. 24, 1920.

Application filed June 18, 1920. Serial No. 390,040. Term of patent 14 years.

To all whom it may concern:

Be it known that I, BENJAMIN F. CRISENBERRY, a citizen of the United States, residing at Indianapolis, in the county of Marion and State of Indiana, have invented a new, original, and ornamental Design for a Food-Masher, of which the following is a specification, reference being had to the accompanying drawing, forming part thereof.

The figure is a perspective view of a food masher, showing my new design.

I claim:

The ornamental design for a food masher, as shown.

BENJAMIN F. CRISENBERRY.
